(57) **CLAIM**

The ornamental design for a spray gun, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a first embodiment of a spray gun showing our new design;

FIG. 2 is a right side elevation view thereof;

FIG. 3 is a bottom plan view thereof;

FIG. 4 is a top plan view thereof;

FIG. 5 is a left side elevation view thereof;

FIG. 6 is a front elevation view thereof;

FIG. 7 is a rear elevation view thereof;

FIG. 8 is a perspective view of a second embodiment of a spray gun showing our new design;

FIG. 9 is a right side elevation view thereof;

FIG. 10 is a bottom plan view thereof;

FIG. 11 is a top plan view thereof;

FIG. 12 is a left side elevation view thereof;

FIG. 13 is a front elevation view thereof; and,

FIG. 14 is a rear elevation view thereof.

FIGS. 8-9, 11-12, and 14 include a color component, namely a red ring component along a side fitting, along the top, and facing a back side of the spray gun.

The broken lines in the figures are included for the purpose of illustrating portions of the spray gun that do not form part of the claimed design.
